UNITED STATES PATENT OFFICE.

FRANK J. MATCHETTE, OF MILWAUKEE, WISCONSIN, ASSIGNOR TO THE SERVIDOR COMPANY, OF WILMINGTON, DELAWARE, A CORPORATION OF DELAWARE.

SERVICE-DOOR.

1,324,608.

Specification of Letters Patent. Patented Dec. 9, 1919.

Application filed November 20, 1915. Serial No. 62,494.

To all whom it may concern:

Be it known that I, FRANK J. MATCHETTE, a citizen of the United States, residing at Milwaukee, in the county of Milwaukee and State of Wisconsin, have invented a certain new and useful Improvement in Service-Doors, (Case 6,) of which the following is a full, clear, concise, and exact description, reference being had to the accompanying drawings, forming a part of this specification.

My invention relates to service doors.

The object of the invention is to provide an inexpensive and efficient service door for the same general class of service as that indicated in my copending application, Serial No. 852,533, filed July 23rd, 1914 now patent No. 1,222,964 dated Apr. 17, 1917. A further object is to provide gravity control mechanism for a lock suitable for use in service cabinets or the like.

In the accompanying drawings which form a part of the present specification, I have illustrated the manner in which my invention may be carried out.

Figure 1 is an outside elevation of a door constructed in accordance with my invention;

Fig. 2 is an enlarged vertical section partly broken away through the cabinet showing the construction of the walls of the cabinet and of the doors;

Fig. 3 is an outside elevation of a modification;

Fig. 4 is an inside elevation;

Fig. 5 is an isometric view with parts broken away of the lock and the gravity control for the lock;

Fig. 6 is a vertical sectional view on an enlarged scale taken just inside the cabinet on the side of the lock stile of the door, showing the locking, the gravity control, and the signaling mechanism;

Fig. 7 is a horizontal section taken just above the signaling mechanism, as shown in Fig. 6; and

Fig. 8 is a fragmentary elevation of the signaling mechanism.

The service door illustrated in the above drawings is of the general type disclosed in my co-pending application, Serial No. 844,622, filed June 12th 1914. The door itself forms a closure for an opening in a

building or the like, and consists of a cabinet 1 inclosed or surrounded by the top and bottom rails 2 and 3 respectively, and the hinge and lock stiles 4 and 5, respectively. It is not essential that these parts be made of separate pieces, and my designation of them as separate parts of the door, is merely for the purpose of designating their position and use, and I intend thereby to designate merely the marginal or frame portion of the door itself. The cabinet 1 is preferably divided up into a number of compartments, 6, 7, 8 and 9, as shown in Fig. 1, extending the full width of the cabinet or a number of smaller compartments of less extent.

In Fig. 3 I have illustrated a form of door in which a number of larger compartments, 10, 11 and 12, and a plurality of smaller compartments, 13 and 14, are provided. These chambers are formed by partitions in the cabinet itself and a door closes the outside of each individual compartment, while a single door, 15, closes all of the compartments on the inner side of the cabinet. In the door shown in Fig. 1, the compartments, 6, 7, 8 and 9, are closed by the doors, 16, 17, 18 and 19 respectively, and in the form shown in Fig. 3, compartments, 10, 11, 12, 13 and 14, are closed on the outside by the doors, 20, 21, 22, 23 and 24, respectively. The inner door 15 is provided with a suitable lock, preferably of the type which can be released only from the outside of the cabinet, as by means of the handle 25. Each door is suitably hinged so as to be easily operable in opening and closing.

The cabinet 1 is secured to the frame members of the door, and the junction of the cabinet and these frame members is finished off by the angle molding 28 on each side of the main door.

The door 16, on the outside of cabinet 6, is provided with a handle 26 forming part of a suitable combination lock. The doors on the other cabinet are provided with handles 27, which are connected with suitable spring latches, as will be described later. Upon the rear of the cabinet, small sight openings 29 for each one of the compartments, is cut through the marginal portion of the cabinet, adjacent the edge of the door 15. Back of each sight opening 29, a target

30 is supported in such relation as to swing into and out of indicating position to apprise the housewife or maid upon the inside of the main door, of the condition of the 5 cabinets, that is, whether they are filled or empty. A fin or cam 31 is secured to the outer compartment door as, for instance the door 17 shown in Fig. 6, and a similar fin or cam member 32 is secured to the single 10 inner door 15. The bracket 33 is secured to the side of the cabinet, as shown in Fig. 7, so that the arm or lever 34, which is pivoted to the bracket at 35, and which bears the target 30 at one end thereof, will be in 15 suitable position to be operated by the cams 31 and 32. The pivoted arm 34 is provided at its outer end with a lateral extension 36 which is long enough to extend within the path of the cam 31. The opposite end of 20 the arm 34 is similarly provided with an extension 37, which, as shown in the particular embodiment illustrated in Fig. 7, may consist of an extension of the target 30, which is secured to the end of the arm 34. The 25 extension 37 projects into the path of the cam 32. The bracket 33 is provided with a lateral extending portion 38 which is suitably slotted to allow swinging of the arm 34 which projects through the slot. The 30 outer end of the arm is provided with a lug 39 and a spring 40 connects the lateral extension 38 and the lug 39 so as to give the indicating arm 34 a snap action after it is once pushed slightly past the central or neutral position. The pivot 35 is so positioned with respect to the cams 31 and 32, that the ends of the arm 34 will be moved up and down to bring the projections 36 and 37 alternately into and out of the paths of the 35 cams 31 and 32 respectively.

I shall now describe the gravity lock control which I prefer to employ with this type of service door. I shall describe the lock and control employed and illustrated specifically with respect to the compartment 7.

A suitable spring latch 41 is secured to the inside of the door 17 adjacent the margin thereof so that the projecting bolt 42, which is provided with an inclined surface 50 on its inner face, may engage the edge of the cabinet and form a catch to prevent the door 17 from opening after the spring bolt 42 is moved into place, as shown in Fig. 5.

The top of the bolt 42 is provided with a 55 notch 43 and the front part of the bolt is provided with an inclined face 44. A vertical controlling bar 45 is mounted on the edge 46 of the cabinet 1, being loosely secured to this edge by means of headed pins 60 47 and 48, which pass through the slots 49 and 50 in the bar itself. The upper end of the controlling bar 45 is provided with a detent 51 for engaging the notch 43 in the top 65 of the bolt 42. The bottom of the bar 45 is provided with a foot or extension 52, which

projects out over the rim of the pan 53. The pan 53 is secured adjacent one edge thereof through a bracket 54 which has a downwardly projecting pivot portion 55 resting in a groove 56 in the bottom of the compartment, and a counterbalance extension 57 for holding the pan 53 normally in the level position. When an article is deposited in the pan 53, the pan tilts downward until it engages the projection 58 in the bottom 75 59 of the compartment. The controlling bar 45 normally resting upon the edge of the pan, loses its support and drops downward, causing the detent 51 to engage the notch 43 in the bolt 42. It will then be impossible to withdraw the bolt 42 and the compartment 7 is inaccessible from the outside. As soon as the housewife or maid 80 opens the inner door 15 and removes the article from the pan 53, the counter balance 85 57 will raise the controlling bar 45 and release the bolt 42 so that the same may be withdrawn and the door opened to permit access to the compartment 7.

The signaling mechanism operates in conjunction with the above as follows:

When the parts are in the position shown in Fig. 6, the outer door 17 may be opened by the purveyor to place a package within the compartment. As the door 17 is opened, the cam 31 engages the projection 36 and throws the arm downward past the center point, where it remains under the influence of the spring 40 holding the target 30 in indicating position before the aperture or 100 sight opening 29. As the package is deposited in the pan 53, the same moves downward overbalancing the weight 57. The controlling bar 45 drops at the same time, since it loses its support from the rim of 105 the pan 53. When the door 17 is closed by the purveyor, the bolt 42 which is spring pressed, noses under the detent 51 raising the same to the point where it will drop into the notch 43 and will again prevent 110 withdrawal of the bolt 42.

The upper compartment door 16 (see Fig. 1) is provided with a combination lock which is preferably not provided with gravity control.

The upper compartment 6 may be reserved for such uses as handling laundry. The laundry is placed in the compartment 6 by the housewife and the driver being provided with the combination of the lock, may remove the articles and when the work on them has been finished, they are returned in the same manner. The occupant of the premises is apprised of the removal of the articles to be laundered by operation of the indicator and as the indicator will be set back to the non-indicating position as soon as the inner door 15 is opened, the occupant will again be apprised of the return of the laundered articles by setting of the 125 indicator and as the indicator will be set back to the non-indicating position as soon as the inner door 15 is opened, the occupant will again be apprised of the return of the laundered articles by setting of the 130 indicator.

proper indicator. The small compartments may be each provided with a separate indicator if so desired.

I have shown the cabinet 1 as constructed 5 of sheet metal. It is to be understood that the frame part of the door may also be made up of metal or of part metal and part wood as may be found convenient. The inner and outer doors for the cabinet are constructed 10 of double thickness of sheet metal suitably flanged to fit the opening in the cabinet and form a tight closure therefor. The openings for the various compartments are flanged as shown at 46 in Fig. 2. The doors are reinforced 15 as shown by the channel member 61 between the inside and the outside sheets of metal.

I do not desire to be limited to the precise details of construction that I have described 20 and illustrated, but intend that the appended claims be construed with all due liberality in view of the prior art.

What I claim is:

1. The combination with a compartment 25 having an opening therein of a door for closing said opening, means including a lock bolt normally operable from outside said compartment for controlling the opening of said door, and article controlled means within 30 said compartment for interlocking with said bolt to prevent withdrawal of said bolt to unlocking position when an article is placed within said compartment.

2. The combination with a compartment 35 having an opening therein of a door for closing said opening, means including a lock bolt normally movable to and from locking position for controlling the opening of said door, and article controlled means within 40 said compartment for interlocking with said bolt to prevent movement of said bolt to unlocking position.

3. The combination with a compartment 45 having an entrance of a door for closing said entrance, a lock for said door having a bolt normally movable to and from locking position, a movable article support within said compartment and a detent controlled by said movable support for locking said bolt in locking position when an article is placed on 50 said support.

4. The combination with a compartment 55 having an entrance of a door for closing said entrance, a lock for said door normally operable from outside said compartment for controlling the opening of said door, a movable article support within said compartment, and means controlled by said support for locking said bolt in locking position when 60 an article is placed on said support.

5. In combination, a compartment, a door 65 for said compartment, a lock for said door, said lock having a spring bolt, a detent for engaging said bolt, to prevent withdrawal of the same, a movable support controlling said

detent, means for holding said support in normal position, said support being moved from normal position by deposit of an article thereupon to cause said detent to engage said bolt. 70

6. In combination, a compartment, a door on each side of said compartment, one of said doors having a spring latch, said latch having a bolt for holding the door closed, a pan in the bottom of said compartment, a 75 connection between said pan and said bolt to prevent withdrawal of said bolt, when an article is deposited in said pan.

7. In combination, a compartment, doors on opposite sides of said compartment, a 80 lock for one of said doors, a spring bolt for said lock, said bolt having a notch therein, a vertical rod having a detent for engaging said notch, and a movable support for controlling said vertical rod. 85

8. In combination, a compartment, having a door on each side thereof, a lock for one of said doors, said lock having a spring bolt for holding the door closed, a controlling bar having means for engaging said 90 bolt and a pivoted pan in the bottom of said compartment for controlling said bar to hold the bolt against withdrawal.

9. In combination, a compartment having doors on opposite sides thereof, a lock for 95 one of said doors, a bolt for said lock, said bolt having a recess therein, a controlling rod having a portion for engaging said recess to prevent withdrawal of said bolt, and a pivoted pan for controlling said rod. 100

10. In combination, a compartment, a door for said compartment, a lock for said door, said lock having a bolt with a recess therein, a vertical rod mounted at the edge 105 of said cabinet adjacent the door, said rod having a portion adapted to engage the notch in said bolt, and having a projecting portion adjacent the bottom of said rod, and a pivoted pan for engaging said latter projecting portion. 110

11. In combination, a compartment, a door for said compartment, a lock for said door, said lock having a spring bolt, a pivoted pan in the bottom of said compartment, a counterbalance weight for said pan, a detent for engaging said bolt to hold same against withdrawal, said detent being controlled by the position of said pan. 115

12. In combination, a service cabinet having doors on opposite sides thereof, a pivoted pan in the bottom of said cabinet, locking means for one of said doors, and interlocking means for said locking means to hold the same against release, said interlocking means being controlled by said pan. 120

13. In combination a hollow cabinet having door openings, said cabinet having in-turned flanges about said openings, doors for closing said openings, said doors being hinged at the edges of the openings, a spring 130

bolt for each door, said bolt engaging behind the flange to hold the door closed, a vertical latch bar, said latch bar and bolt having inter-engaging parts to hold the bolt against withdrawal when the latch bar engages the same, and means for guiding said vertical latch bar along the inturned flange.

14. In combination a hollow cabinet having door openings, said cabinet having in-turned flanges about said openings, doors for closing said openings, said doors being hinged adjacent the edges of the openings, a spring latch for each door, said spring latch having a bolt for projecting behind the flange to hold the door closed, pins on the rear side of said flange, a vertical latch bar lying against said flange and having slots which fit over said pins, said latch bar and bolt having inter-engaging parts to hold the bolt against withdrawal when the latch bar engages the same.

15. In combination a hollow cabinet having door openings, said cabinet having in-turned flanges about said openings, doors for closing said openings, said doors being hinged adjacent said openings, a spring latch for each door, said spring latch having a bolt engaging behind the flange to hold

the door closed, a vertical latch bar, said latch bar and bolt having inter-engaging parts to hold the bolt against withdrawal when the latch bar engages the same and a support pivoted to the bottom of the cabinet, said support having means for holding the latch bar in raised position.

16. In combination a hollow cabinet having door openings, said cabinet having in-turned flanges about said openings, doors for closing said openings, said doors being hinged at the sides of said openings, a spring latch for each door, said spring latch having a bolt engaging behind the flange to hold the door closed, a vertical latch bar slideable along said flange, said latch bar and bolt having inter-engaging parts to hold the bolt against withdrawal when the latch bar engages the bolt, a pan pivoted upon the bottom of the cabinet near one side thereof, and a weight for counterbalancing the pan and latch bar, said latch bar having its end overlying the edge of the pan.

In witness whereof I hereunto subscribe my name this 17th day of November, A. D. 1915.

FRANK J. MATCHETTE.
